United States Patent Office.

E. P. FORD, OF SHIPMAN, ILLINOIS.

Letters Patent No. 91,006, dated June 8, 1869.

IMPROVED WEATHER-STRIP.

The Schedule referred to in these Letters Patent and making part of the same.

To all whom it may concern:

Be it known that I, E. P. FORD, of Shipman, in the county of Macoupin, and State of Illinois, have invented a new and useful Improvement in Weather-Strips; and I do hereby declare that the following is a full, clear, and exact description thereof, which will enable others skilled in the art to make and use the same, reference being had to the accompanying drawings, forming part of this specification.

This invention relates to a self-acting weather-strip, to be attached to outside doors for stopping wind and rain; and

The invention consists in the construction and arrangement of the strip and the parts connected therewith, as hereinafter more fully described.

In the accompanying sheet of drawings—

Figure 1 is a sectional side elevation of a door provided with my weather-strip.

Figure 2 is a vertical section of fig. 1 through the line *x x*.

Figure 3 is a detached view of the guide and stop-plate.

Similar letters of reference indicate corresponding parts.

A is the door.

B is the door-casing.

C is the door-sill.

e is the threshold or raised portion of the sill.

f is a plate of metal on the threshold, against which the weather-strip acts in closing.

g is the grooved stop and guide-plate, by which the action of the strip is controlled.

H is the self-adjustable weather-strip.

This strip H is placed in the groove *i* of the door, with its lower edge protruding below the bottom of the door.

It is slotted at the ends, and its lower edge is bevelled, as seen in the drawing.

The ribs or partition *j*, in the guide-plates *g*, act as stops, and limit the rise and fall of the strip.

The strip is forced upward, in closing the door, by striking the threshold and plate *f*, as seen in fig. 2, where the position of the strip and the stop-plate *g* is seen in red color, as when closing.

The position of the strip, after the door is closed, is seen in the same figure.

It will be seen that the strip rises and passes over the plate *f* in closing the door, when it drops by its own gravity into the position seen in the drawing.

The bevelled edge of the strip corresponds with the bevelled edge of the plate *f*, and effectually excludes wind and water.

The bar or stop *j* prevents the strip from dropping too low when the door is open, and the groove *k*, in the plate *g*, keeps the strip in its proper position at all times.

It will be seen that no springs are used to insure a perfect working of the strip, and none are necessary. The arrangement is very simple, and not likely to get out of order.

The plates *g* are attached to the edges of the door, and form a perfect guide and stop for the strip.

Having thus described my invention,

I claim as new, and desire to secure by Letters Patent—

In combination with a door, the strip H, and the guide and stop-plate *g*, constructed, combined, arranged, and operating substantially as and for the purpose herein shown and described.
